DESIGN FOR A BRASSIÈRE OR SIMILAR ARTICLE

George A. Kaufmann, Essex Fells, N. J., assignor to The H & W Company, Inc., Newark, N. J., a corporation of New Jersey

Application June 16, 1939, Serial No. 85,517

Term of patent 7 years

To all whom it may concern:

Be it known that I, George A. Kaufmann, a citizen of the United States, residing at Essex Fells, county of Essex, State of New Jersey, have invented a new, original, and ornamental Design for a Brassière or Similar Article, of which the following is a specification, reference being had to the accompanying drawing, forming a part thereof.

Fig. 1 is a front view of a brassière with the back tab of Fig. 2 omitted showing my new design; Fig. 2 is a back view of the same with the front tabs of Figs. 1 and 3 omitted; and Fig. 3 is a perspective view of the brassière shown in Fig. 1 with the back tab of Fig. 2 omitted.

I claim:

The ornamental design for a brassière or similar article, as shown.

GEORGE A. KAUFMANN.
